WINDOW SHADE

Henry Hill Collins, Bryn Mawr, Pa.

Application April 10, 1934, Serial No. 719,936

1 Claim. (Cl. 156—10)

This invention relates to improvements in window shades and more particularly in that class of window shades composed of translucent material.

A principal object of the invention is to provide a translucent shade of practicable form having superior ornamental characteristics.

Another object is to provide a decorated translucent shade in which the ornamental markings are protected from the deteriorating effects of the sun.

Translucent shades of the type now in general use and of the usual construction are not adapted to ornamentation. Ornamental figures imposed on such shades produce an undesirable splotched appearance on the translucent background and color values are largely destroyed. Also the ornamental markings being exposed to the sunlight are subject to rapid deterioration and fading. Attempts to provide opaque areas on the body of the shade as a suitable background for ornamental figures have involved such substantial changes in the structure of the shade or have so adversely affected the general appearance as to render the shades commercially valueless.

I have found it possible, by the present invention, to provide a translucent shade having a marked and highly desirable ornamental appearance which in no essential respect departs from the accepted standard construction and which constitutes a readily manufacturable and highly commercial article.

The invention will be readily understood from the attached drawing which shows in perspective a shade comprising a body portion 1 of a suitable flexible translucent material such as paper or textile fabric. The shade departs from the usual construction in that it is provided at the lower depending end with a decorated pocket 2, which may vary in width according to the character of

the decoration. In this pocket is inserted a wooden strip 3 or strip of other opaque material which neatly fits the pocket. Without material modification in the standard shade construction, I thus provide at the lower end of the shade an opaque area of sufficient dimension to receive an adequate ornamental design which being confined entirely to the opaque section shows to full advantage, is not subject to fading by sunlight, and does not adversely affect the appearance of the transparent main section of the shade.

Shades of this character may be readily manufactured by printing, lithographing, or otherwise decorating detached strips of the shade material which are then suitably attached to the main body 15 of the shade; or the decoration may be made on the end of the shade itself. If the first method is used, a section of the shade material may be printed in one operation with a plurality of relatively spaced decorated bands and subsequently 20 divided to provide the individual decorated strips which are attached to the body of the shade as described. The depth of the pocket may be made to conform with the size and character of the desired design. It will be understood, however, 25 that the methods of forming the pocket and producing the ornamental design may vary without departure from the invention.

I claim:

A shade of flexible translucent material having 30 a transverse pocket adjoining the depending end, said pocket being of substantial depth, a relatively stiff substantially opaque reinforcing strip fitting said pocket, and an ornamental design on at least one face of said shade confined entirely 35 to the portion thereof embraced by the pocket and backed by said substantially opaque reinforcing strip.

HENRY HILL COLLINS.
